ABSTRACT

A reducer head for rotary-swaging machines, wherein an inner and an outer shaft together hold therebetween a working tool including a plurality of axially spaced ring members. Means are provided for effecting an output signal pulse upon each rotation of the head, such means including an insulating insert in one of the rings to chop a DC current fed through such ring and a current collector in sliding contact with the ring, the ring member and current collector rotating relative to each other. In this manner a direct readout may be made of the rotational speed and hence the number of swaging operations per unit time.

SHEET 1 OF 2

FIG. 2

REDUCER HEAD OF AUTOMATIC ROTARY-SWAGING MACHINE FOR REDUCING METAL WIRE PARTS

The present invention relates generally to rotary-swaging machines and more particularly, to reducer heads of rotary-swaging machines for reducing metal wire parts. The invention can find the most effective application when employed in duplicate or large scale production by the rotary-swaging method.

A typical known reducer head comprises an outer spindle and an inner spindle arranged one inside the other, adapted to rotate cooperatively and to hold working tool therein, and a roller holder through which the outer spindle is free to run, said roller holder being adapted to interact with said working tool; said inner spindle featuring a bore for the metal wire to pass, has a drive to impart axial motion thereto.

Such known reducer head, however, features no devices or means whatever to monitor the number of swagings of the part to be reduced and to control that number, which makes it impossible to correctly specify the main process characteristics of the reduction procedure.

It is an object of the present invention to eliminate the above-mentioned disadvantages.

It is the main object of the present invention to provide such a reducer head that would ensure a possibility of determining the number of swagings of the metal wire under process and controlling that number within the required limits.

The main object is accomplished due to the fact that the reducer head of a rotary-swaging machine for reducing metal wire parts, comprising an outer spindle and an inner spindle arranged one inside the other, adapted to rotate cooperatively and to hold a working tool therein, and a roller holder through which said outer roller runs and which is adapted to interact with said working tool, said inner spindle featuring a bore for the metal wire to pass therethrough and having a drive to impart axial motion thereto, according to the invention incorporates a device to measure and control the rotational speed of the roller holder and, consequently, the number of swagings the metal wire is subjected to per unit of time.

The device for measuring and controlling the number of revolutions of the roller holder may comprise an adjustment ring mounted inside the housing of the reducer head pivotally with respect to said housing and adapted to act upon the roller holder, and a counter for measuring the number of revolutions performed by the roller holder.

It is expedient that the adjustment ring may be imparted turning motion with respect to the housing of the reducer head by virtue of a worm-and-sheel transmission whose worm sheel is rigidly connected to said adjustment ring.

It is also desirable that an electric impulse counter serve as the counter for measuring revolutions made by the roller holder, said counter being connected to one of the rings of the roller holder by way of a current-collector located in the adjustment ring and contacting the surface of the roller holder ring that carries an insert made of an insulating material.

The herein disclosed reducer head with a device for measuring and controlling the number of revolutions of the roller holder, makes it possible to determine the number of swagings of the metal wire per unit of time and to control it within the required limits which in turn allows of correctly selecting the appropriate technological characteristics upon which both the quality and efficiency of the reducing process are dependent.

Given hereinbelow is a detailed description of a preferred exemplary embodiment of the present invention to be read in conjunction with the relevant drawings annexed thereto, wherein:

FIG. 1 represents a perspective view, partly in section, of a reducer head of an automatic rotary-swaging machine for reducing metal wire parts, featuring a device for determining and controlling the number of revolutions of a roller holder, according to the invention; and

FIG. 2 is a fragmentary, longitudinal section view of the reducer head of FIG. 1.

Reference being now directed to the appended drawings, the reducer head of an automatic rotary-swaging machine of the invention comprises an outer spindle 1 (FIG. 1) and an inner spindle 2 arranged one inside the other and adapted to rotate with respect to each other, a roller holder 3, a drive 4 to impart axial motion to the inner spindle 2 and a device 5 for measuring and controlling the number of revolutions of the roller holder 3. The outer spindle 1 and the inner spindle 2 are provided coaxial with slots and carry a working tool comprising cooperating strikers 6 and dies 7 arranged in respective slots of the spindles and engaging with each other along their inclined surfaces. The outer spindle 1 runs through the roller holder 3 whose rollers 8 are adapted to interact with the strikers 6 of the working tool. The inner spindle has a bore 9 for the metal wire to pass through.

The roller holder 3 comprises essentially two oppositely arranged axially spaced and rigidly interconnected rings 10 and 11. The rollers 8 are so interposed between said rings 10 and 11 as to be free to rotate about the axes of such rollers.

The device 5 for measuring and controlling the revolutionary speed of the roller holder comprises an adjustment ring 12 mounted in a housing 13 of the reducer head so as to be free to rotate with respect to said housing by means of a worm gearing comprising an annular worm wheel 14 (FIG. 2) which is rigidly connected to the adjustment ring 12 and a worm 15 engaging the worm wheel 14 and mounted in a housing 16 made fast on the housing 13. Rotation of the worm 15 is effected by means of a handle (not shown in the drawing), the degree of rotation thereof being obtained from a suitable counter (not shown in the drawing).

The adjustment ring 12 with its inner face is in contact with the ring 11 of the roller holder 3, said latter ring carrying a segment-shaped insert 17 made of an insulating material.

Additionally, a current collector 18 is mounted in the adjustment ring 12, said current collector being likewise in contact with the surface of the ring 11 of the roller holder. The current collector 18 is connected to an electric impulse counter (not illustrated in the drawing) through a wire 19, said counter serving to count the number of revolutions of the roller holder.

The reducer head of the invention operates as follows.

The drive electric motor (not appearing in the drawing) having been switched on, the outer spindle 1 starts rotating, said spindle being connected with the motor through sprockets 20 (FIG. 1) and by way of chain transmission (not shown in the drawing).

Rotation of the outer spindle 1 compels the rotation of the inner spindle 2 together with the working tool, i.e., the strikers 6 and the dies 7.

As a result the strikes 6 and the dies 7 are urged by centrifugal force in the radial direction away from the axis of the reducer head so that the strikers 6 come into contact with the rollers 8 of the roller holder 3, and under the effect of the rollers 8 the strikers move in the direction towards the axis of the reducer head and the dies effect reduction of the metal wire by swaging. Periodicity of the reducing process is governed by the drive 4 for imparting axial displacement to the inner spindle 2, said drive comprising a cam 21 kinematically connected with the outer spindle 1 through a mechanism for cutting off finished parts (said mechanism being not shown in the drawing). The cam 21 is connected also with the inner spindle 2 through levers 22, 23 and a coupling 24 that is rigidly connected to the spindle in axial direction. With the motor switched on the cam 21 starts rotating thus imparting axial displacement to the inner spindle 2.

The dies 7 move together with the spindle 2 in the axial direction relative to the stationary strikers 6 along their juxtaposed inclined surfaces. When the inner spindle 2 moves to the left the dies draw together to effect the reducing or swaging process, and when the spindle 2 moves to the right together with the dies 7 the latter move apart, discontinuing the reducing process.

Rotation of the working tool compels the rotation of the roller holder 3 entrained thereby. To obtain the number of revolutions made by that roller holder, a low-voltage direct current is passed between the roller 11 of the roller holder and the electric impulse counter (not shown in the drawing). Each individual revolution of the roller holder 3 brings about a breakage of the electric circuit at the moment when the insert 17 (FIG. 2) is passing by the current collector 18, said breakage being registered by the electric impulse counter. The number of pulses delivered per unit of time by the current collector 18 to the electric impulse counter 18, is equal to the number of revolutions performed by the roller holder 3 per unit of time.

With the known number of revolutions of the roller holder 3, one can obtain the coefficient of slippage of said holder relative to the outer spindle 1 and the inner spindle 2 by making resort to the following formula:

$$f = n_1/n_2,$$

where

n_1 indicates the number of revolutions performed by the roller holder 3 per unit of time,

n_2 indicates the number of revolutions made by the outer spindle 1 and the inner spindle 2 per unit of time.

The value of f being known, one can determine the number of swagings of the metal wire made per unit of time, by having recourse to the formula that follows:

$$m = f n_2 p,$$

where p denotes the number of the rollers 8 in the roller holder 3.

Thus knowing the number m of swagings of the metal wire per unit of time, it is made possible to correctly and appropriately specify and assign the process characteristics of the reduction procedure.

Moreover, the device 5 is instrumental in governing the number of revolutions of the roller holder 3. This may be effected as follows.

The rotation of the worm 15 compels the rotation of the

worm wheel 14 and the adjustment ring 12 associated therewith which in this case will either be screwed in or screwed out of the housing 13 of the reducer head, thereby varying the force exerted upon the ring 11 of the roller holder 3 with the result that the number of revolutions of the latter will likewise be varied and, consequently, the number of swagings of the metal wire performed per unit of time.

We claim:

- 10 1. A reducer head of a rotary-swaging machine for reducing metal-wire parts, comprising an outer spindle mounted in a housing an inner spindle having a bore for the metal wire to pass through, said inner spindle being located inside said outer spindle and being adapted to rotate in cooperation therewith; a drive to impart axial displacement to said inner spindle; a working tool held in said outer and inner spindles; a roller holder through which said outer spindle runs, said roller holder being adapted to interact with said working tool; a device for measuring and controlling the number of revolutions of said roller holder, said device serving for counting the number of swagings of the metal wire performed per unit of time and comprising an adjusting ring mounted inside said housing and adapted to turn with respect thereto to interact with said roller holder during rotation thereof, and a counter for counting the number of revolutions of said roller holder, said adjusting ring and said counter being electrically interconnected.
- 15 20 25 30 35 2. A reducer head as defined in claim 1, wherein worm gear means are provided to enable said adjusting ring to turn relative to the reducer head housing, the worm wheel of said worm gear means being rigidly secured to said adjusting ring.

3. A reducer head as defined in claim 1, comprising an electric impulse counter for counting the number of revolutions of said roller holder, a current collector located in said adjusting ring and maintained in contact with said roller holder, and an insert made of an electrically insulating material and arranged on said roller holder at the point where the latter is in contact with said current collector.
